POSTING UNIT

Oscar S. Field and Sedgwick N. Wight, Rochester, N. Y., assignors to General Railway Signal Company, Rochester, N. Y.

Application June 5, 1943, Serial No. 489,776

13 Claims. (Cl. 177—327)

This invention relates in general to airway traffic control systems, and has more particular reference to a posting unit particularly adapted for use in such airway traffic control systems.

In systems of the type referred to, such as disclosed, for example, in the application of Field and Wight, Ser. No. 489,774, filed June 5, 1943, now Patent No. 2,344,761, dated March 21, 1944 and entitled "Airway traffic control systems," an airway flight progress board is provided on which are automatically posted various numbers, for identifying particular planes, computed times of arrival, overtime, etc. The posting unit, such as provided for by the present invention, may be used to form the flight progress board for use in such a system to effect the postings of these various identifying numbers.

This application which is directed to the structural features of a posting unit is to be considered as a continuation in part of our prior application Ser. No. 470,018 filed December 24, 1942, insofar as the structure of the posting unit per se disclosed in such prior application is concerned. Any subject matter common between this application and such prior application is intended to be covered by claims included in this application.

One of the objects of the present invention is to provide a posting unit which is very small and compact in structure and hence most economical of space on the flight board.

Another object of the present invention is to provide a posting unit which is simple in construction and still is very rugged and hence long lived in operation.

A further object of the present invention is to provide a posting unit which lends itself to ready inspection, for adjustment, and possible repair.

A further object is to provide such a unit as can be readily reassembled without the breaking of any wire connections, in the proper former relative positions of the various parts, so as to prevent any possible error in the performance of its posting function. This is accomplished, in the main, by providing quickly detachable plug coupler type of connections between the various parts.

A further object of the invention is to provide a posting unit of an interchangeable type controllable by different and interchangeable contact control heads.

Further objects, purposes, and characteristic features of this invention will appear as the description progresses, reference being made to the accompanying drawings, showing, solely by way of example, and in no manner whatsoever in a

limiting sense, one form which the invention can assume.

In the drawings:

Fig. 1 is a plan view of one complete posting unit in accordance with this invention.

Fig. 2 is a side elevational view of the posting unit of Fig. 1.

Fig. 3 is an end elevational view of the display portion of the posting unit of Fig. 1, and a sectional view of the display portion of two adjacent posting units.

Fig. 4 is a side elevational view of the display portion of the posting unit of Fig. 1, with parts shown in section.

Fig. 5 is a sectional view on line 5—5 of Fig. 4, and viewed in the direction of the arrows.

Fig. 6 is a longitudinal sectional elevation with parts shown in elevation of the contact control portion of the posting unit of Fig. 1.

Fig. 7 is a longitudinal elevational exploded view of Fig. 6.

Fig. 8 is a sectional view on line 8—8 of Fig. 6, and viewed in the direction of the arrows.

Fig. 9 is a sectional view on line 9—9 of Fig. 6, and viewed in the direction of the arrows.

Fig. 10 is a partial sectional view of a second form of the invention.

Fig. 11 is a sectional view on line 11—11 of Fig. 10 viewed in the direction of the arrows.

Fig. 12 is a schematic view of circuits employed in this invention.

Referring now to the drawings, and considering the first form of invention, (Figs. 1—9), there is here shown, by way of example, a complete posting unit, as employed in the system of the application above referred to. Although but a single posting unit is disclosed in detail in this application, it can be readily understood from the system of the application above referred to that a large number of such units is employed, but since they are identical, it is sufficient for the purpose of the present disclosure to limit the description in general to but a single unit.

From Figs. 1 and 2, it appears that each unit is operated from a main shaft MS which can be continuously operated by a motor or the like, not shown, and the unit is normally automatically held out of driving connection with the main shaft. The display portion of the posting unit, as described below, is operated by a display shaft DS on the inner end of which a drive gear DG is fastened as by means of a pin 10.

The contact control portion of the posting unit, as described below, is operated by a shaft CS to the inner end of which a gear CG is fastened as

by a pin 11. The gear DG is wide and has teeth 12 which are always in mesh with teeth 13 on gear CG. Thus, as appears more clearly below, gear DG can be moved to the left to bring a friction face 14 thereon into frictional engagement with a like face 15 on a drive wheel 16 pinned to the main shaft as at 17 without thereby disengaging the gears DG and CG. By means of this arrangement, the display portion and the contact control portion of the posting unit can be driven from main shaft MS upon gear DG being advanced toward shaft MS all as described more fully below.

Referring now more particularly to Fig. 6, shaft CS passes through a fixed housing member 18 which rotatably receives main shaft MS. Received on housing 18 is one part 19 of a two-part separable casing having a second part 20 with both parts formed of suitable insulating material as Bakelite or the like. These two-part casings 19 and 20 fit together in a telescoping manner with part 20 slideable on a receiving portion 21 of casing part 19 to form a quick detachable plug coupling arrangement as appears more clearly as the description progresses.

Casing part 19 is fixed to housing 18 by means of screw 22, while casing part 20 is non-rotatably held on portion 19 by means of a positioning pin 23 in part 20 and projecting inwardly thereof to be received in a slot 24 extending longitudinally inwardly from the inner end of part 19. With this arrangement, it can be seen that if casing portion 20 be removed from 19, it can again be replaced thereon in exactly the same position as it formerly assumed, by reason of this positioning pin 23 and receiving groove 24.

Removably held in the free end of casing part 20 is a plug member comprising a portion 25 slidably fitting into the end of part 20 and having a semicircular annular groove 26 in which is received a split circular ring 27 which, when in holding position, expands outwardly into a semicircular annular groove 28 in the inner face of part 20. In this way, plug member 25 can be readily inserted into, and removed from the casing part 20.

Plug member 25 receives a threaded stud 29 which clamps various contact members to the plug member. These contact members include an outer cup-shaped contact ring 30 of silver or like material, having inspection openings 31 therein, and an inner cup-like contact ring 32 of silver or like material. Member 32 is in electrical contact with stud 29, while member 30 is insulated therefrom and from member 32 by insulating washers 33. A terminal member 34 is clamped by stud 29 against member 30, while a second terminal member 35 is clamped together with an insulating washer 36 against the head of stud 29 and serves as a terminal for the inner cup member 32.

These inner and outer contact cup members 32 and 30 cooperate with a plurality of contact points, such as 37, carried on contact fingers, such as 38, to which fingers are connected pushers as 39 as by riveting or the like with the contact fingers, as 38, connected to the removable casing part 20 of the plug coupler arrangement as by means of screws 40.

Though but a single contact finger has been specifically referred to above, in reality there are ten contact fingers carried by the casing part 20, and these fingers are arranged around the circumference of the member as can be clearly seen from the fingers 41, 42, 43, etc. The ten contact fin-

gers correspond to the ten digits 0-9, respectively, and the significance of this will be seen as the description progresses.

For each contact finger, as 38, there is a terminal wire contact part as 44, fastened in a receiving slot 45 by a screw 46 in casing part 19. To the inner end of this contact part 44 can be fastened an energizing wire, such as 47, by soldering it or connecting it in any other desired manner. The other end of each contact part, as 44, has an upturned end, as at 48, to bear against its corresponding contact finger when the plug coupler is connected up, two of the contact fingers having inwardly bent ends, as at 49, for example, to aid in locking together the two parts 19 and 20 of the plug coupler when it is assembled.

Each contact finger, as 38, has a pusher, as 39, as described above, which is received in an opening, as 50, in the casing member 20 and projects inwardly thereof a short distance whereby to be contacted and operated by a cam member in the form of a roller 52 of fiber or like material held by a pin 53 in a bifurcated end 54 of a head 55 pinned, as at 56, to the contact shaft CS. When shaft CS is rotated, the cam successively operates on each pusher to move it outwardly and break the normal connection of the contact points, as 55, with the inner ring 32 and make contact with the outer ring 30 as shown in connection with contact point 37.

As appears from the above description, head 55 turns relatively to a shaft supporting member 58 which is held against rotation by means of a pin 59 carried thereby and received in the slot 24 of the casing part 19. To prevent accidental turning of cam 52 and its head when the plug coupler end is removed, a friction brake is employed, which comprises a spring 61 sleeved on shaft CS and urging member 58 against head 55 to compress therebetween a friction washer or brake member 62. The desirability of preventing such accidental turning of the cam will appear as the description progresses.

As can be seen from Fig. 7, which is an exploded view and similar to Fig. 6, the removable part 20 of the plug coupler can be readily removed from, and replaced on the fixed part 19, all as described above and as here shown. Furthermore, the end portion of coupler member 20 can be readily removed and replaced as also shown in Fig. 7, and with it, the parts carried thereby including the inner and outer conducting rings 30 and 32.

As shown more particularly in Fig. 4, for example, the display portion of the posting unit is controlled by the drive shaft DS which carries the drive gear DG, as described above, and which gear is pinned to its shaft as by pin 10. This gear DG carries a sleeve portion 65 on the inner face of which is formed a series of teeth 66 forming V-shaped depressions 67, ten in number, to correspond to the tens digits 0-9 with a function which will appear as the description progresses.

Cooperating with these depressions 67 is a round-headed projecting pin 68 fixed in a fixed hub 69, which hub is carried by an electro-magnet cup-like fixed frame 70. Shaft DS has pinned to it a magnetic plunger or core 71 carrying a magnetic armature 72 of a disc-like form for cooperating magnetically with the shell-type magnetic casing or cup 70 within which is an electric winding 74.

Pinned to plunger 71, as by pin 75, is a shaft 76 slideable in a yoke 77 fastened, as at 78, to a base plate 79.

Shaft 76 is pinned, as at 80, to a cup-like mem-

ber 81 within which is received a biasing spring 82, and which cup-like member has forwardly projecting teeth 83 slidably received in apertures 84 in a bevel gear 85 received on and rotatable with shaft 76.

The bevel gear 85 is in mesh with a bevel gear 87 fastened to a spur gear 88 which is in mesh with the teeth of a gear 89 formed on the base of a display cylinder 90 which is mounted for rotation in a bearing 91 suitably fastened to base plate 79.

Display cylinder 90 is made of translucent material such as frosted glass, milk glass, or the like, and carries on its inside face, and distributed around its circumference, the ten digits 0-9.

Within cylinder 90 is a source of light in the form of a lamp 92 positioned in a receiving socket 93 whereby, when energized, the light shines through the translucent cylinder 90 and makes the normally invisible digits on the inside of the cylinder clearly visible to an observer on the outside.

The base plate 78 is formed of any suitable material as metal, and along its two outer longitudinal edges is turned downwardly at right angles to the main floor portion of the plate to form two supporting runners 94 and 94¹ whereby the complete display portion of the posting unit can be slid into a receiving housing formed, as shown best in Fig. 3, by vertical side plates 95 and 96 and angle irons 97, 98, 99 and 100.

The showing in Fig. 3 includes not only the unit just described and which is displaying the digit 1 but also an adjacent unit with the front window removed, and in which the digits 2, 1, 0 are visible, and a portion of a unit 101 above this last mentioned one, and likewise a portion of a unit 102 below it. At its rear portion, the base plate is cut on a longitudinal central line part way towards the front end of the plate, and these portions are bent upwardly and outwardly at right angles to the floor portion to form two spaced supporting sides, one of which, 105, is shown best in Fig. 2, for supporting the electro-magnet unit. This unit is held in place as by screws 106 and 107. The front end of the base plate is turned upwardly at right angles to the floor portion and in front of the display cylinder 90 and is cut out centrally to form a part of a window as defined by the two spaced vertical panels 108 and 109. Connected to this up-turned front end portion of the base plate is a stop and window plate 110 in which is formed a window 111 through which the digit to be displayed can be seen by an observer at the front of the unit, under lighted conditions, the particular digit shown displayed in Fig. 3, being 1.

Fastened to the underside of the base plate and within the space afforded by the plate and runners 94 and 94¹ is an insulating plate 113. To this insulating plate are fixed two contact members 114 and 115 contacting respectively with the base and with the socket of the lamp. For energizing coil 74 there are two contact members 117 and 118 fastened to the insulating plate and extending rearwardly to terminate in plug coupler ends 119 and 119¹. In like fashion, contacts 114 and 115 terminate at the rear of the display portion of the posting unit in plug coupler ends 120 and 121.

Fastened to the floor portion of the receiving casing formed by the side plates and angles is an insulating strip 122 which carries four inlet contact fingers 123, 124, 125 and 126 for cooperating, respectively, with the contact members 117, 115, 114 and 118, respectively, when the unit is in

place in the housing. This forms a plug coupler type of display unit which can be readily removed from its housing and re-inserted thereinto without the necessity for breaking any fixed wire connections.

The display portion, when inserted into its housing, is limited in its insertion by plate 110 at its front which butts against the upper end of the housing, as at 127.

Referring now to Figs. 1 and 2, it can be seen that upon energization of winding 74, armature 72 and core member 71 move toward and into the winding, whereby to disengage the socket 67 from pin 68 and advance the drive gear DG into frictional engagement with friction drive wheel 16. Thereupon, main shaft MS drives gear DG which, as set forth above, is always in mesh with gear CG so that contact shaft CS and display shaft DS are rotated to operate controlling cam 52 and display cylinder 90.

As set forth in the system circuit case above referred to, and shown in Fig. 12 (and disclosed more particularly in Fig. 15A, etc. of the above identified application 489,774), the control of the posting unit depends upon placing energy on any one only of the ten contact fingers 43, etc., by means of wire connections (not shown), which results in placing energy on coil 74 through a circuit including the inner ring 32. This energy remains on the coil, and the drive continues until the cam breaks the circuit by lifting the particular energized finger away from the inner ring. Upon this occurring, the coil becomes deenergized, and spring 82 disengages the drive and reengages the opposing one of the sockets 67, etc. with pin 68 to immediately brake the display device and center it with the proper digit accurately positioned in the display window. It should be borne in mind that the sockets 67, etc. are so positioned as to accomplish this, and that they are ten in number to correspond with the ten digits on the display cylinder. The circuits for accomplishing these functions have not been shown since this case is concerned primarily with the structure of one of the many posting units to be employed in the system case above referred to.

When the energized contact finger is lifted from the inner ring and makes contact with the outer ring, this completes a circuit and the energization of such circuit, so as to check various other functions, or so as to repeat the same display accomplished by this particular posting unit at some other location, on the same operator's control board, all as more clearly set forth in the referred to system case.

The control of the posting unit is vested in any one of a large number of tokens of a type as disclosed in application, Ser. No. 489,775, filed June 5, 1943, in the names of O. S. Field and S. N. Wight and entitled "Token and receptacle for airway traffic control systems."

It can be appreciated from the above description that for inspection, repair or replacement of parts, the structure lends itself to the ready accomplishment of such operations. The display portion of the posting unit can be withdrawn from its housing, as a unit, from the display cylinder 90 up to and including the drive gear DG. Furthermore, the contact control unit can be removed in the manner indicated in Fig. 7, etc., the plug coupler portion 20 can be removed, and further, the end plug portion 25 can be removed from the portion 20.

It should be noted that each contact finger, as 75 44, corresponds to a particular digit on the display

cylinder, as, for example, finger 44, which cooperates with finger 38 when the plug coupler is assembled and carries contact point 37 corresponding as shown in the drawings, with the digit 1. It is essential that the parts be initially positioned so that this correspondence or any other arbitrarily chosen correspondence exists. Thereafter, should the parts be removed, they must be replaced in their former positions, as otherwise, the energization of a particular finger, to display the corresponding digit, will result in the display of some other digit.

To insure maintenance of this proper correspondence, it can be seen that the display portion of the posting unit, after being withdrawn from its housing, must be replaced in its exact former position, as determined by a dowel pin 130 carried by the housing and receivable in a matching hole 131 in the electromagnet casing.

In a like manner, for maintenance of the proper correspondence between the parts, the pin 23 in the removable part 20 of the plug coupler is received in slot 24 in the fixed part of the plug coupler whereby to insure the proper reassembling of the plug coupler. Also, pin 59, in the stationary head 58, is received in this same slot 24 so as to prevent this head 58 from rotating while allowing it to slide on shaft CS. This sliding of head 58 permits spring 61 to compress the braking washer 62 between the head and the collar 55, whereby to prevent accidental turning of cam 52 and its carried parts when the plug coupler is separated and the display portion of the posting unit is removed. If, under these stated conditions, the cam were rotated, the predetermined correspondence referred to above might be changed with the result of faulty posting.

The plug 25 and its parts when removed from the plug coupler part 20, can be reassembled in any position without any chance of error arising, since contact rings 30 and 32 are continuous.

Since a large number of posting units is required in the system, as disclosed in the system case referred to above at each of the fixes or check points, it is essential, in order that the airway flight board be not prohibitively large, that these units be very compact and economical in use of space. In this particular case, each housing member for receiving the display portion of a posting unit is in the order of a one-inch square. It can be appreciated from this that for identifying a plane having a number, including three digits, such as 123, three complete posting units, such as described above are required, i. e., one for each digit.

As stated above, this posting unit can be controlled by a token, as disclosed in the above referred to token application. In such application, a token when inserted in a socket completes three separate circuits in a distinctive manner to thereby energize one of the ten fingers on each of three posting units. This causes the operation of each of these three posting units until the proper number appears in the window at the front of the unit, at which time the unit is de-energized and posting of the proper plane identification is effected.

A somewhat modified form of the invention is shown in Figs. 10 and 11, wherein the contact control portion of the posting unit is of a different construction from that shown in Fig. 6, for example, and described above. In this form, the contact control portion is changed from the former construction only with regard to the removable portion of the plug coupler arrangement.

As in the first form, there is a removable plug coupler part 140 removably fitting onto a stationary part 141. This removable part 140 carries ten contact fingers, as 142, arranged around the periphery of the part and having riveted to them pushers, as 143, which are operated as described above by a cam 144. Each finger has a contact point, as 145, biased to normally contact with an inner continuous conducting ring 146 but operable by the cam to break connection with this inner ring and to make contact with the corresponding one of ten isolated outer fixed contact strips, as 147, arranged around an insulating block 153 and connected thereto by screws 1471.

Also connected to each of the pushers, as pusher 143, is a second contact finger 148 which is in electrical contact with its associated finger and extends beyond this associated finger and carries a contact point 150 which contacts with a continuous conducting outer ring 151 when in its cam operated position. These fingers 149 are biased to normally rest against an intermediate insulating block 152, between which block and outer block 153, is clamped the continuous ring 151. Ring 151 has a lead-out connector 154 for connection to external circuits, while the inner ring 146 has a lead-out connector 155 which is in electrical contact with its ring by way of a clamping bolt 156 which is similar to the corresponding bolt employed in the first form of invention, but is somewhat longer than such bolt.

The connecting bolt 156 clamps the various portions together, as obvious from the drawing, and is received in an inner block 157 of conducting material and which is detachably held in place in the removable coupler part 140 by means of grooves and a resilient split ring 160, as in the first form. The extending contact fingers, as 149, are apertured, as at 161 to freely receive the contact points, as 145, on the outer fingers, as 142.

From the above description, it can be readily appreciated that the cam 144, when operated, successively moves the outer fingers away from making contact with the inner ring, and into making contact with the isolated strips, as 147, while at the same time, the extending contact fingers are moved successively, from an inactive biased position to an active operated position into contact with the continuous outer ring 151.

The posting unit, in the modified form just described, differs from the posting unit as described in connection with the first form only with regard to the removable part of the coupler.

Accordingly, by simply removing this part of the plug coupler from the fixed part and replacing it by the modified form of removable part, the posting unit can be changed from the one form to the other. This makes for easy and economical interchangeability of the form of posting unit and is a distinct advantage since both forms, in large numbers, of posting units are employed in the system case referred to above.

In this modified form of posting unit, the control of the posting at the "fix" at which the unit is located, is controlled as before by breaking contact of the proper outer finger with the inner ring all as shown in Fig. 12 in connection with the first described form of invention. The function of the inner fingers in connection with the outer ring and of the outer fingers in connection with the strips, as 147, is involved in the transfer or repeating of the posting at one "fix" to another fix on a different operator's control board.

The various circuit arrangements and connec-

tions for effecting this function are not described in this specification since they do not constitute any part of this particular invention, and for details in this connection, reference should be made to the system case referred to above.

The above rather specific description of two forms which the invention can assume, has been given solely by way of example and is not intended, in any manner whatsoever, in a limiting sense. It is to be understood that various modifications, adaptations and alterations may be applied from time to time to meet the requirements of practice without, in any manner, departing from the spirit or scope of the invention, except insofar as limited by the appended claims.

Having described our invention, we now claim:

1. In posting units for airway traffic control systems, in combination, a posting unit having a display part and a contact control part, a driven shaft for each part, a main drive shaft, means for operably and simultaneously connecting the main shaft, to the two driven shafts, the control part including, a fixed casing, a removable casing quickly detachably securable on the fixed casing, a plurality of contact strips on the fixed casing, a like plurality of contact fingers on the removable casing positioned to contact, respectively, with the strips, when the two casings are interconnected, a removable plug in the removable casing, an inner and a spaced outer, conducting ring carried by the plug, the control part shaft extending through the fixed casing and into the removable casing, a contact operating cam on the shaft, and contact points on the contact fingers movable by the cam from contact with one ring to contact with the other.

2. In posting units for airway traffic control systems, in combination, a posting unit having a display part and a contact control part, a driven shaft for each part, a main drive shaft, means for operably and simultaneously connecting the main shaft, to the two driven shafts, the control part including, a fixed casing, a removable casing quickly detachably securable on the fixed casing, a plurality of contact strips on the fixed casing, a like plurality of contact fingers on the removable casing and positioned to contact, respectively, with the strips when the two casings are interconnected, a removable plug in the removable casing, an inner and a spaced outer, conducting ring carried by the plug, the control part shaft extending through the fixed casing and into the removable casing, a contact operating cam on the shaft, and contact points on the contact fingers movable by the cam from contact with one ring to contact with the other, the contact fingers and the contact strips being positioned around the outside of their casings, an operating pusher on each contact finger, an aperture in the removable casing for each pusher and loosely receiving its pusher, the contact fingers being biased to position the pushers to extend inside of the casing and opposed to the cam.

3. In posting units for airway traffic control systems, in combination, a posting unit having a display part and a contact control part, a driven shaft for each part, a main drive shaft, means for operably and simultaneously connecting the main shaft to the two driven shafts, the control part including, a cylindrical fixed casing, a removable cylindrical casing quickly detachably securable on the fixed casing, a plurality of contact strips on and spaced around the fixed casing, a like plurality of contact fingers on and spaced around the removable casing and posi-

tioned to contact, respectively, with the strips when the two casings are interconnected, a removable plug in the removable casing, an inner, and a spaced outer, conducting ring carried by the plug, the control part shaft extending through the fixed casing and into the removable casing, a contact operating cam on the shaft, contact points on the contact fingers movable by the cam from one ring to the other, an operating pusher on each contact finger, an aperture in the removable casing for each pusher and loosely receiving its pusher, the contact fingers being biased to position the pushers to extend inside of the casing and opposed to the cam, and mechanically interengaging means on the fixed and removable casings, respectively, for requiring assembly of the casings always in the same relative position.

4. In posting units for airway traffic control systems, in combination, a posting unit having a display part and a contact control part, a driven shaft for each part, a main drive shaft, means for operably and simultaneously connecting the main shaft, to the two driven shafts, the control part including, a cylindrical fixed casing, a cylindrical removable casing quickly detachably securable to the fixed casing, a plurality of contact strips on and around the outside of the fixed casing, a like plurality of contact fingers on and around the outside of the removable casing, and positioned to contact, respectively, with the strips, when the two casings are interconnected, a removable plug in the removable casing, an inner, and a spaced outer, conducting ring carried by the plug, the control part shaft extending through the fixed casing and into the removable casing, a contact operating cam on the shaft, contact points on the contact fingers movable by the cam from contacting with one ring to contacting with the other ring, an operating pusher on each contact finger, an aperture in the removable casing for each pusher, and loosely receiving its pusher, the contact fingers being biased to position the pushers to extend inside of the removable casing and opposed to the cam, and friction brake means between the shaft of the contact control part and the fixed casing, to prevent accidental turning of the shaft when the removable casing is removed.

5. In posting units for airway traffic control systems, in combination, a posting unit having a display part and a contact control part, a driven shaft for each part, a main drive shaft, means for operably and simultaneously connecting the main shaft, to the two driven shafts, the control part including, a cylindrical fixed casing, a cylindrical removable casing quickly detachably securable to the fixed casing, a plurality of contact strips on and around the outside of the fixed casing, a like plurality of contact fingers on and around the outside of the removable casing, and positioned to contact, respectively, with the strips, when the two casings are interconnected, a removable plug in the removable casing, an inner and a spaced outer, conducting ring carried by the plug, the control part shaft extending through the fixed casing and into the removable casing, a contact operating cam on the shaft, contact points on the contact fingers movable by the cam from contacting with one ring to contacting with the other ring, an operating pusher on each contact finger, an aperture in the removable casing for each pusher, and loosely receiving its pusher, the contact fingers being biased to position the pushers to extend inside of the removable casing and opposed to the cam, polarizing means on the 75 fixed and removable casing for requiring assembly

of the casings always in the same position, and friction brake means between the shaft of the contact control part and the fixed casing, to prevent accidental turning of the shaft when the removable casing is removed.

6. In posting units for airway traffic control systems, in combination, a posting unit having a display part and a contact control part, a driven shaft for each part, a main drive shaft, means for operably and simultaneously connecting the main shaft, to the two driven shafts, the control part including, a fixed cylindrical casing, a removable cylindrical casing quickly detachably securable to the fixed casing, a plurality of contact strips on and arranged around the fixed casing, a like plurality of contact fingers on and arranged around the removable casing and positioned to contact, respectively, with the strips, when the two casings are interconnected, a removable plug in the removable casing, an inner and a spaced outer, conducting ring carried by the plug, the control part shaft extending through the fixed casing and into the removable casing, a contact operating cam on the shaft, contact points on the contact fingers movable by the cam from contacting with one ring to contacting with the other, an operating pusher on each contact finger, an aperture in the removable casing for each pusher and loosely receiving its pusher, the contact fingers being biased to position the pushers to extend inside of the casing and opposed to the cam, an extending contact finger and contact point on each pusher and in electrical contact with the other finger on the pusher, and a second outer conducting ring on the plug and cooperating with the contact points of the extending fingers.

7. In posting units for airway traffic control systems, in combination, a posting unit having a display part and a contact control part, a driven shaft for each part, a main drive shaft, means for operably and simultaneously connecting the main shaft, to the two driven shafts, the control part including, a fixed cylindrical casing, a removable cylindrical casing quickly detachably securable to the fixed casing, a plurality of contact strips on and arranged around the fixed casing, a like plurality of contact fingers on and arranged around the removable casing and positioned to contact, respectively, with the strips, when the two casings are interconnected, a removable plug in the removable casing, an inner and a spaced outer, conducting ring carried by the plug, the control part shaft extending through the fixed casing and into the removable casing, a contact operating cam on the shaft, contact points on the contact fingers movable by the cam from contacting with one ring to contacting with the other, an operating pusher on each contact finger, an aperture in the removable casing for each pusher and loosely receiving its pusher, the contact fingers being biased to position the pushers to extend inside of the casing and opposed to the cam, the extending fingers passing between the inner and the first said outer ring, and an aperture in each extending finger loosely receiving the contact point of the other finger on the same pusher.

8. In posting units for airway traffic control systems, in combination, a posting unit having a display part and a contact control part, a driven shaft for each part, a main drive shaft, means for operably and simultaneously connecting the main shaft, to the two driven shafts, the control part including, a fixed cylindrical casing, a removable cylindrical casing quickly detachably securable to the fixed casing, a plurality of contact strips

on and arranged around the fixed casing, a like plurality of contact fingers on and arranged around the removable casing and positioned to contact, respectively, with the strips, when the two casings are interconnected, a removable plug in the removable casing, an inner and a spaced outer, conducting ring carried by the plug, the control part shaft extending through the fixed casing and into the removable casing, a contact operating cam on the shaft, contact points on the contact fingers movable by the cam from contacting with one ring to contacting with the other, an operating pusher on each contact finger, an aperture in the removable casing for each pusher and loosely receiving its pusher, the contact fingers being biased to position the pushers to extend inside of the casing and opposed to the cam, and means anchoring the removable casing against rotation when in assembled position on the fixed casing.

9. In posting units for airway traffic control systems, in combination, a posting unit including a control part and a display part, a main drive shaft, a driven shaft in each of said parts, biased lock means for normally positively locking both driven shafts against rotation, release means operable for unlocking the driven shafts and simultaneously drivably connecting them to the main shaft, a plurality of conducting contacts operably connected to the control part shaft so as to be successively operated when their shaft turns, a turnable display box operably connected to the display part shaft so as to turn when its shaft turns, and different indicia of a number equal to the number of said plurality of contacts, distributed around the box, the control part including a plug member and a plug member receiving socket member, each of said plurality of contacts including a plug portion carried on the plug member, and a socket portion normally in contact with its plug portion and carried on the socket member, the plug and socket members being quickly, detachably connectable together, and cooperating mechanically interengaging means in the two members respectively for requiring the connection of the two members in an invariable position in which the same plug and socket portions of contacts are always electrically interconnected when the members are interconnected.

10. In posting units for airway traffic control systems, in combination, a posting unit including a control part and a display part, a main drive shaft, a driven shaft in each of said parts, means operable for drivably connecting the driven shafts to the main shaft, a plurality of contacts operably connected to the control part shaft so as to be successively operated when their shaft turns, a turnable display means operably connected to the display part shaft so as to turn when its shaft turns, and different indicia, of a number equal to that of said plurality of contacts, distributed around the means, the control part including quickly detachable plug and socket members, each of said plurality of contacts including a plug portion carried on the plug member, and a socket portion carried on the socket member, cooperating pin and slot means in the two members for assuring the interconnection of the two members in an invariable position in which the same plug and socket portions of contacts are electrically interconnected when the members are interconnected, and a second alternative plug member, having a different arrangement of contact plug portions, removably securable on the said socket member, so

that the contact plug portions cooperate with the socket contact portions.

11. In a posting unit for an airway traffic control system, a driven shaft located longitudinally of the unit and normally biased longitudinally in one direction, electromagnetic means for actuating said shaft longitudinally against its bias for engaging a power-driven clutch to cause rotation of said shaft, detent means for normally preventing rotation of the shaft when it is in its normal biased position but releasing said shaft for rotation when it is actuated by said electromagnetic means, a display drum mounted on an axis at right angles to the axis of said driven shaft, and means operatively connecting said drum to said shaft irrespective of the position of the shaft to thereby cause the display drum to be rotated when said power-driven clutch is engaged but to be held in its existing position when said shaft is in its biased position.

12. In a posting unit for an airway traffic control system, a driven shaft located longitudinally of the unit, a coil spring surrounding the shaft and normally biasing it longitudinally in one direction against a stop, an electromagnet having a winding surrounding said shaft and a circular armature attached to said shaft for causing the endwise movement of said shaft against said biasing spring when said winding is energized, a centering detent means including a circular member attached to said shaft and having a recess for each of a plurality of positions and a fixed centering member receivable in the nearest one of said recesses when said shaft is biased to its normal position by said coil spring, a power-driven clutch engaged by said shaft when it is caused to be moved endwise by said electromagnet for causing rotation of the shaft, a display drum mounted on an axis at right angles to said driven shaft, and means including a beveled gear

5 mounted on said shaft to allow endwise movement of the shaft with respect to the gear but causing the gear to be rotated when the shaft rotates for causing the rotation of said drum to its different positions.

13. In a posting unit for an airway traffic control system, a display drum having a plurality of different display positions and mounted to be rotated on an axis parallel with the plane of an 10 aperture in the face of the unit, a driven shaft located longitudinally of the unit and normally biased longitudinally in one direction against a stop, an electromagnet having a winding surrounding said shaft and a circular armature attached thereto for causing the actuation of said shaft away from the stop when said winding is energized, a power-driven clutch engaged by said shaft when it is in an actuated position for causing rotation of the shaft, means operatively connecting 15 said shaft with said display drum to cause rotation to its different positions when said power-driven clutch is engaged, a separate contact unit having a contact for each position of said display drum and operably connected to said shaft through a sliding gear connection, and a 20 centering detent means including a circular member having a toothed recess for each position of said display drum and a fixed centering member receivable into said recesses when said shaft is biased against the stop, whereby said display drum is caused to be centered in the selected 25 display position and the contact for the corresponding position is positively held when said electromagnet is deenergized irrespective of the slight off center stopping of said shaft for any 30 selected position when said power-driven clutch is disengaged.
